UNITED STATES PATENT OFFICE.

ALFRED BRYANT MORSE, OF BOSTON, MASSACHUSETTS, ASSIGNOR, BY MESNE ASSIGNMENTS, TO THE UNIVERSAL WINDING COMPANY, OF BOSTON, MASSACHUSETTS, A CORPORATION OF MAINE.

WINDING-MACHINE.

SPECIFICATION forming part of Letters Patent No. 695,645, dated March 18, 1902.

Application filed June 27, 1898. Serial No. 684,585. (No model.)

To all whom it may concern:

Be it known that I, ALFRED BRYANT MORSE, of Boston, county of Suffolk, State of Massachusetts, have invented an Improvement in 5 Winding-Machines, of which the following description, in connection with the accompanying drawings, is a specification, like letters on the drawings representing like parts.

My present invention is an improvement 10 on thread-winding machines, particularly those of the kind patented to me December 11, 1896, No. 572,309, and has for its object the production of a more compact and simplified machine capable of a greater range of 15 usefulness, increased economy in running, and saving of power.

In my former machine the throw-cam is mounted on a shaft parallel to the main or driving shaft and having bearings in a swing- 20 ing bracket.

In my present construction I have done away entirely with much of the mechanism shown in my said patented winding-machine and have mounted the throw-cam directly on 25 the main shaft, my invention also including the provision of a construction which enables me to change the machine for winding a short cone or bobbin readily or a long one, as desired. Again, in my patent the machine re- 30 quires a considerable alteration and readjustment of parts to convert it from winding a cone to winding a parallel quill, and accordingly another object of my present invention is the provision of simpler means for chang- 35 ing from cone-winding to cylinder or parallel winding, or vice versa.

Further improvements of my present invention will be more fully apprehended in the course of the following detailed description, reference being had to the accompanying drawings, illustrative of the preferred embodiments thereof, and the invention will be more particularly defined in the appended claims.

45 In the drawings, Figure 1 is a front elevation of the complete machine, excepting a suitable base or support. Fig. 2 is a dia- grammatic top or plan view illustrating the adjustment of the machine for winding dif-

ferent forms of thread masses. Fig. 3 is a 50 right-hand end elevation of the machine shown in Fig. 1. Figs. 4 and 5 are respectively views in central longitudinal section and end elevation of a detail of construction.

In suitable standards a a' I journal a main 55 shaft b , herein shown as provided with usual fast and loose pulleys b' b'' , driven from a belt b^3 . Between the standards and loosely journaled on the main or driving shaft b between collars c c' is a throw-cam d , herein shown as 60 having its hub d' reduced, as indicated by dotted lines at d^2 , to receive a driving-gear e , secured thereto by means of a set-screw e' .

The shaft b is provided with a suitable speed-changing device, herein shown as composed of cones f f' , belt f^2 , and belt-shifter f^3 , all of any usual or preferred kind for suitably changing the speed to correspond to different requirements of the work.

The pulley f' is mounted on a stub counter-shaft journaled in the standard a' and provided at its opposite end with a pinion g , meshing with an intermediate gear or idler g' , geared in turn to the driving-gear e of the throw-cam, it being understood that the train 75 of gear as thus arranged is provided for convenience in driving the throw-cam, it being preferable that the latter should rotate in the same direction as the main shaft.

Loosely mounted on a fixed sleeve surrounding the shaft b between the standard a and a collar c^2 is a bracket h , having an extended hub h' and split at its upper end to receive a spindle i , held in clamped position by a bolt h^2 , this spindle being provided at its upper 85 end with bearings i^2 , carried by a yoke i^3 , rigid with said spindle. In said bearings i^2 is journaled the quill-spindle k , having a gear k' fast thereon between the bearings i^2 and driven from a gear k^2 , fast on the main 90 shaft, through an intervening idler k^3 , journaled at k^4 in the bracket h .

The quill-spindle k is held in proper position adjacent the thread-guide m by means of a weight w , suspended from an arm w' , extending rearwardly from the hub h' , Fig. 3.

In my patent above referred to I provided, a compound swinging movement, both the

quill-spindle and the thread-guide swinging together; but in my present invention I have arranged the thread-guide m to reciprocate in a stationary bearing, it being herein shown 5 in the form of an arm carried by a thin tube m' , Fig. 4, mounted on a rod m^2 , fast in the frame of the machine, said tube being provided with a stud or roll m^3 , traveling in the path of the throw-cam, and having an opposite site lug m^4 , traveling in a slot or way m^5 in the frame of the machine for maintaining the proper direction of movement and keeping the thread-guide steady and uniform in its operations.

10 15 It will be understood that the reciprocations of the thread bar and guide are exceedingly rapid, and therefore it is of considerable importance that these parts should be as light as possible. They must, however, have great 20 strength to accomplish the excessive work required of them. I have attained these objects by making the tube m' of thin drawn tubing, which being cylindrical is capable of 25 withstanding great endwise strain without buckling, and in order to insure that the strain shall be endwise without any twisting or buckling tendency I support the tube m' at its ends on annuli m^6 , which fits snugly on the rod m^2 , and not only therefore accurately 30 center the guide-bar, but give a friction bearing-surface and leave an internal air-space of considerable extent between the tube and the rod, which materially aids in reducing the friction, and outside of the annuli m^6 I 35 shrink on the encompassing thread-guide m at one end and a ring at the other end, carrying the stud m^3 and lug m^4 , so that the ends of the tube m' are pinched immovably between the thread-guide and one annulus 40 m^6 at one end and between the stud-support and the other annulus m^6 at the other end.

45 The thread, twine, or other material t being wound passes from any usual source over rolls p p' , as in my patent, and thence to a tension-wheel p^2 and other tension mechanism, the same as in my patent, excepting that instead of the crank employed in my 50 patent I here provide a rack-bar p^3 , meshing with a pinion p^4 , sleeved on the spindle of the tension and having fast to it a disk p^14 , in turn provided with a pin p^15 , to which is attached one end of a strap p^16 , running over and in contact with the hub of the tension-wheel and sustaining at its end the weight p^17 . The 55 rack-bar is pivoted at p^5 to the arm w' on the hub h' referred to.

60 I prefer a rack-bar and pinion to the connecting-rod and crank shown in my patent, for the reason that it is more certain in its operation and permits of a wider range of movement for the different requirements of the machine. It is a very simple matter to remove one pinion p^4 and replace another, larger or smaller, but having the same pitch 65 of teeth.

On the bar p^3 is mounted an adjustable stop s , arranged to engage a stop-motion lever h^8 ,

constructed and operating substantially as the correspondingly-lettered part shown in my patent. This lever is normally held in locking engagement with a rod h^4 by a dog s^3 , whose arm s^4 rests lightly on the thread t , so that when the latter breaks the dog s^3 will move the lever h^8 sufficiently to disengage it from the rod h^4 and permit the spring h^7 on 75 the latter to shift the belt b^3 and stop the machine.

I find that in practice with a machine constructed as described the thread will not wind properly, or at least it will not wind to 80 the best advantage when the quill is free to bear against the thread-guide with the full force of the weight w , and accordingly I have devised an automatic grip which relieves the pressure on the thread-guide of the surface 85 of the quill in winding, thereby preventing the excess of friction, which would otherwise prove seriously objectionable. This automatic grip will be understood, viewing Fig. 3, where it will be seen that I have provided 90 a finger or rod r , pivoted at r' to the arm w' and held and sliding in a passage provided in a bracket r^2 , secured to the frame of the machine. A lever r^3 , freely pivoted on a stud r^4 and preferably provided with a roll r^5 at 95 its engaging end, rides against the finger r , being normally held in biting engagement therewith by a spring r^6 in a cup r^7 engaging the outer free end of the lever.

Viewing Fig. 3, where the dotted line indicates the dead-center position of the lever, it will be observed that this lever r^3 is in a position to always permit the finger or rod r to move upwardly, but to prevent its moving downwardly, and accordingly it will be understood that the rod or finger r is automatically gripped and held by the lever r^3 as the thread mass increases on the quill, so that whatever outward movement is gained by the thread mass moving away from the thread-guide is held, and the quill is automatically prevented from swinging back again toward the thread-guide, even to the minutest degree.

I find in practice the rapid rotation of the cop or thread mass acts to throw the spindle and mass just far enough away from the thread-guide to give the required ease of movement, and this advantage is never lost, because the clutch r' prevents any return of the mass into close contact with the thread-guide. This also prevents any rebounding of the thread mass and proves of great advantage in the practical running of the machine.

I have provided a shim-like back r^8 as a bearing-surface for the rod or finger r , which may be delicately adjusted by means of the set-screws r^9 .

As the thread mass builds up on the quill the quill-spindle and its support swing away 130 from the thread-guide on the main shaft as a center, and from this explanation and viewing Fig. 3 it will be readily understood that the button of the thread-guide maintains its

path of movement approximately in the same plane relatively to and embracing the axis of the quill-spindle, and by reason of the fact that the arc of movement of the quill-spindle

5 is at substantially the same radial distance from the main shaft as the delivery end of the thread-guide it will be observed that I do not need to vary the position of the thread-guide, as done in my patent above mentioned.

10 It will also be understood that when it is desired to wind any different form of thread mass or to wind a cylinder it is a very simple matter simply to loosen the clamping-bolt ^{h2} and turn the quill-spindle in its support so 15 as to bring the surface of the quill next the thread-guide into parallelism with the latter. Also it will be understood that the arrangement of parts as described enables me very readily to change the throw-cam from the cam 20 such as shown to a larger or a smaller throw-cam, as may be desired, limited only by the dimensions of the parts of the machine.

Inasmuch as the moving parts are much more compact and are simpler than those here- 25 tofore provided, I am enabled to run the machine at a much higher speed and obtain a largely-increased output.

The slide-bar for the thread-guide constructed as shown is much cheaper, lighter, 30 and less liable to get out of order than the plate slide-bars heretofore provided.

I do not intend to limit my invention to the precise details of construction herein shown, but contemplate various changes and modifi- 35 cations as coming within the spirit and scope of my invention. Some of these I have indicated.

My invention possesses further novelties, as hereinafter claimed.

40 It will be understood that where I have used the word "preferable" in this specification I mean thereby that I am not limited to certain features of construction herein shown and described when certain other features of 45 my invention are being considered, and, moreover, I wish it understood that I do not limit myself otherwise than as expressed in the claims.

Having fully described my invention, what 50 I claim as new, and desire to secure by Letters Patent, is—

1. A thread-winding machine, having a main or driving shaft, a throw-cam loosely mounted thereon, driving means for said 55 throw-cam, a bracket loosely pivoted on said shaft, a quill-spindle carried by said bracket, gearing fast on the main shaft and on the quill-spindle, connections for said gearing, whereby the quill-spindle is positively rotated 60 by said shaft, a thread-guide co-operating with the quill-spindle on said swinging bracket, and means to reciprocate said thread-guide, substantially as described.

2. A thread-winding machine comprising a 65 main or driving shaft, a throw-cam loosely mounted thereon, means driven by said shaft for driving said throw-cam in the same di-

rection of rotation as said main shaft, a quill-spindle, and a thread-guide, and means to reciprocate said thread-guide, substantially as 70 described.

3. A thread-winding machine having a main or driving shaft, a throw-cam loosely mounted thereon, driving means for said throw-cam, a bracket loosely pivoted on said shaft, a 75 spindle extending radially of said shaft and pivotally mounted in said bracket, bearings carried by the outer end of said spindle, a quill-spindle mounted in said bearings transversely of said pivoted spindle, gearing be- 80 tween said shaft and said quill-spindle for driving the latter from the former, a thread-guide, and means actuated by said throw-cam for reciprocating said thread-guide, substan- 85 tially as described.

4. In a winding-machine, a thread-guide, a stationary bearing therefor, means for reciprocating said thread-guide, a quill-spindle adjacent said thread-guide, a swinging support for said quill-spindle, means for adjusting 90 said quill-spindle in said support angularly to the path of movement of said thread-guide, and means mounted to swing with said swinging support, for rotating the spindle, substan- 95 tially as described.

5. In a winding-machine, a stationary bearing for a thread-guide, said thread-guide, means to reciprocate it, said thread-guide traveling always in the same plane, a swing- 100 ing quill-spindle arranged to swing in an arc approximately including the path of move- 105 ment of the button of the thread-guide, said thread-guide and quill-spindle being arranged tangentially for the thread mass to bear di- rectly against the thread-guide as the thread is being wound, and means to uniformly ro- 110 tate said spindle, substantially as described.

6. In a winding-machine, a stationary bearing for a thread-guide, said thread-guide, means to reciprocate it, said thread-guide 110 traveling always in the same plane, a swing- 115 ing quill-spindle arranged to swing in an arc approximately including the path of move- 120 ment of the button of the thread-guide, said thread-guide and quill-spindle being arranged tangentially for the thread mass to bear di- rectly against the thread-guide as the thread is being wound, and driving devices to posi- 125 tively and uniformly rotate said spindle, sub- 130 stantially as described.

7. In a winding-machine, a thread-guide, means to reciprocate it, a quill-spindle, means permitting relative swinging movement of said quill-spindles and said thread-guide, means to rotate said spindle, and an automatic friction device freely permitting the quill-spindle and the said thread-guide to separate and automatically preventing an opposite movement thereof, said friction device comprising a bearing-surface, a pivoted lever, a rod connected to a moving part of said separating members and moving between said bearing-surface and lever, said lever en- gaging said rod obliquely thereto, and a

means normally tending to make said lever bite said rod, substantially as described.

8. In a winding-machine, a thread-guide, means to reciprocate it, a quill-spindle, a swinging support therefor, means to rotate said spindle, and an automatic friction device freely permitting the quill-spindle to swing away from the said thread-guide, and automatically preventing an opposite swinging movement thereof, said friction device comprising a bearing-surface, a pivoted lever, a rod connected to said swinging spindle and moving between said bearing-surface and lever, said lever engaging said rod obliquely thereto, and a spring device normally tending to make said lever bite said rod, substantially as described.

9. In a winding-machine having a movable quill-spindle, means to rotate it, a thread-guide, and means to reciprocate it, an automatic tension device, said tension device having a pinion for adjusting it, and a rack-bar engaging said pinion and connected to move with said quill-spindle.

10. In a winding-machine, a thread-guide, a stationary bearing therefor, and a slide-bar mounted on said bearing, said bar being in the form of a thin tube or cylinder provided with a lug for reciprocating the same and said tube being supported at its ends out of frictional contact with the said bearing, substantially as described.

11. In a winding-machine, a bearing mounted in the frame of the machine, a slot formed in the frame of the machine adjacent and parallel to said bearing, a throw-cam mounted to rotate adjacent said bearing, a slide-bar mounted on said bearing a thread-guide carried by said slide-bar, said slide-bar being tubular, and having a stud projecting therefrom and traveling in the path of the throw-cam,

and a lug also projecting therefrom and traveling in said slot in the frame for keeping the thread-guide steady, substantially as described.

12. In a winding-machine, a stationary bearing, and a slide-bar mounted on said bearing, said bar comprising a thin tube supported coaxially of the rod by an annulus adjacent each end, a thread-guide surrounding said tube at one end and holding the tube between it and the contained annulus, and a ring carrying a stud at the other end, the tube being held between said ring and the adjacent annulus at the said end, substantially as described.

13. A thread-winding machine, comprising a thread-guide, a guideway for the same, means to carry a quill to receive the material to be wound, a shaft, intermediate devices to rotate said quill-carrying means, a throw-cam mounted loosely on said shaft, and means to rotate said throw-cam at any desired speed about said shaft and in the direction of its rotation, substantially as described.

14. A thread-winding machine, comprising a thread-guide, a fixed guideway therefor, a rotatable throw-cam for reciprocating said thread-guide, a bracket mounted to turn about the center of rotation of said throw-cam, and a quill-carrier sustained revolubly on said bracket and automatically movable about the pivot of the bracket as the mass of thread being wound increases in diameter, substantially as described.

In testimony whereof I have signed my name to this specification in the presence of two subscribing witnesses.

ALFRED BRYANT MORSE.
